SPARK PLUG

Philippe Miron, Saint Boniface, Manitoba,
Canada

Application August 14, 1933, Serial No. 684,935

3 Claims. (Cl. 123—169)

My invention relates to improvements in spark plugs such as are commonly used for igniting a charge in an internal combustion engine and particularly to improvements in the sparking elements and associated parts.

One of the objects of my invention is to provide a spark plug including a metal ball of conductive material movable within a cage or chamber constituting the ground electrode, the said chamber being formed to maintain a uniform sparking relation between the ball and one of the electrodes.

A further object of my invention is to provide an internal combustion chamber in the spark plug with communicating passages for reception of explosion fluids and discharge of the products of combustion, said chamber being designed to maintain the plug free of carbon with consequent improved operation of the sparking elements, and also to assist in heating the spark plug when starting a cold engine so that it will warm up faster.

Other objects of my invention will become apparent from the accompanying description taken in conjunction with the drawing wherein like characters of reference indicate like parts throughout the different views and wherein:

Fig. 1 is a perspective side view of the spark plug assembled.

30 Fig. 2 is a view in vertical section of a spark plug embodying my improvements.

Fig. 3 is an inverted plan view thereof.

Fig. 4 is a fragmentary view, partly broken away and partly sectioned, of the lower end of a 35 plug embodying my improvements but including a separable ball chamber.

Fig. 5 is a sectional view of a separable ball chamber of an extension type for use in certain types of engines.

40 Fig. 6 is a side view of a terminal connector.

Fig. 7 is a plan view of the connector.

While I have shown only the preferred forms of my invention, I wish it understood that various changes or modifications may be made without departing from the spirit of the invention.

Having reference to the drawing, my improved spark plug includes an outer metallic shell 1 threaded at its lower end as indicated at 2 adapted to be screwed into the registering perforation in the cylinder of an internal combustion engine and a centre power electrode rod 3 in a petticoat type core 4 made of insulating material, preferably porcelain, and a gland nut 5 threadably engaging the top of the outer shell as

indicated at 6, the outer shell, core and gland nut are provided with cooperating gasket seats in which asbestos lined gaskets 8 and 9 are interposed. Threaded on the upper end of the power electrode is an end cap 10 with packing 10' between the core and end cap suitably seated in the core, a terminal cap 11 being provided for attachment of the high tension wire.

The lower end of the electrode rod is secured by a collar 12 fixed thereto, said collar being seated in the recess 13 formed in the core 3, the lower end of the electrode rod 3 terminating level with or just short of the lower end of the core 3.

The lower portion of the outer shell 1 provides a cage or chamber 14 with one or more apertures 15—15 for admission of gases from the combustion chamber and within which is moveable a ball 16 of conductive material, the ball, the chamber and the centre electrode being preferably made of ignition alloy.

The outer shell 2 which is grounded to the engine and the centre electrode rod 3 form the two electrodes of a circuit including, a source of power, the high tension wire connecting the upper end of the electrode rod and the source of power. The ball 16 being interposed between the electrodes leaves a gap between one or other of the electrodes and the ball across which a spark is caused to jump when a high voltage current is passed through the circuit.

In order to maintain a uniform sparking relation, it is necessary that the chamber 14 be formed to restrict movement of the ball 16 within certain defined limits designed to maintain a uniform spark gap. The said chamber has its side wall 35 17 flared slightly outward from its lower end and the outer portion of the bottom 18 directed downward with the central portion of the bottom, immediately beneath the centre electrode rod, horizontal leaving a slight depression in the centre of the bottom portion, formed by a relatively flat center section 35 with surrounding downwardly inclined annular section 36. The side wall 17 is of circular formation, upstanding relative to the section 36, said wall being inclined outwardly relative to the plane of the center section 35 of the bottom section, with transverse fluid passages provided by the apertures 15—15.

By this formation of the ball chamber the unbridged gap between the ball and one or other of the electrodes is maintained uniform, irrespective of the position of the ball 16. It has been found that directing the wall 17 outward approximately 18° from the vertical and the outer por-

tion of the bottom 18 about 10° below the horizontal obtains the required uniformity.

By the provision of such a uniform spark gap more efficient and complete firing of the charge 5 in the combustion chamber of the engine under greater compression is obtained with more equal performance of the motor, and the strain on the spark plug is reduced to a minimum with consequent longer life of the plug.

10 The core 4 is formed recessed to provide an annular combustion chamber 19 communicating by an annular passage 20 with the ball chamber 14 and thence, through the openings 15 in the bottom of said chamber, with the engine cylinder within which the spark plug is mounted, the number of said openings 15 varying in accordance with the size of the plug. Explosion fluids under pressure enter the chamber 19 through the openings 15 and passage 20 and by 20 being ignited therein serve to eliminate carbon from the sparking elements as a result of the explosive force and fire applied to said elements. Any carbon remaining will be drawn out on the intake or suction stroke rendering the spark 25 plug self cleaning. In addition the initial explosion within said chamber in starting an engine serves to warm the spark plug and facilitate subsequent explosions. The core 4 includes a tip or end portion 33 of elongated cylindrical formation adapted for co-operation with a section 34 of the shell 1, said section and core end portion extending in parallel relationship defining the passage 20 of relatively narrow elongated 30 formation.

35 In Figure 4 is shown a spark plug embodying my improved ball chamber but in a separable form. In this showing 21 indicates the shell, 22 the core, and 23 the power electrode. Threaded into the shell 21 is an end section 24 providing a 40 ball chamber 25 with ball electrode 26. For adjustment of the connection of said end section 25 with the shell 21 a shim 27 is insertable therebetween permitting variation of the spark gap. In other respects the formation and operation of 45 the sparking elements remains the same.

Fig. 5 shows a separable ball chamber of an elongated character for use in certain types of engines, such as certain tractors, where it is necessary for the sparking elements to be lower in

the combustion chamber owing to peculiarities in formation of the cylinder head.

Figures 6 and 7 disclose an improved terminal connector for the plug which includes a tubular body 28 attachable to a supply cable and having 5 an integral plate 29 with opening 30 engageable over the end portion of the power electrode terminal cap, said opening having a slotted extension 31 for engagement of said terminal cap. On the plate 29 is a spring 32 engageable to lock the 10 connector on to the terminal cap.

It is understood that certain features of the device are useful without reference to other features, and the use of such individual features is contemplated by this invention and is within the 15 scope of the appended claims.

Having thus described my invention, what I claim is:

1. A spark plug comprising a core having an elongated tip portion and an annular recess 20 spaced from the end thereof by said tip portion, and a shell housing said core, wherein said shell and tip portion extend in substantially parallel relationship spaced apart forming a relatively narrow elongated passage communicating with 25 the recess in the core.

2. A spark plug comprising a core having an annular recess formed therein spaced from the lower end thereof defining an elongated end portion and a shell housing said core, wherein 30 the core end portion is of substantially cylindrical formation and the shell includes a section extending in parallel relationship with said end portion spaced therefrom to form a relatively narrow elongated passage communicating with 35 the recess in the core.

3. A spark plug comprising a core and a shell housing said core, said shell including a sparking chamber adapted for reception of a movable element, said chamber including a bottom portion having a relatively flat center section and a downwardly inclined annular section surrounding the center section, and a circular upstanding wall, said wall being inclined outwardly relative to the plane of the center of the bottom section, 45 the bottom section being further formed with transverse fluid passages.

PHILIPPE MIRON.
